UNITED STATES PATENT OFFICE.

PAUL SCHÖNFIELD, OF BOCHUM-WEITMAR, GERMANY.

GRIPPING DEVICE FOR LIFTS AND THE LIKE.

Application filed August 24, 1921. Serial No. 494,962.

To all whom it may concern:

Be it known that I, PAUL SCHÖNFIELD, a citizen of Germany, residing at Bochum-Weitmar, Germany, have invented certain new and useful Improvements in Gripping Devices for Lifts and the like (for which I have filed an application in Germany, August 27, 1920), of which the following is a specification.

10 My invention relates to gripping devices for cages, lift platforms and the like and its object is to prevent clogging of the teeth of such devices by the chips detached from the guide rails, which is the most frequent cause of failure of such gripping devices.

According to my invention, the chips from the guide rails are conducted to the outside in the same direction in which they have been detached. This is achieved by forming 20 the teeth of the gripping clutches after the manner of a grid or railing, so that interstices are left between them which communicate with a chamber provided behind the teeth. The cutting teeth so arranged are 25 united by the lateral cheeks of the chamber. The chips which are detached owing to the engagement of the gripping pawls are discharged to the rear through the interstices. Besides, the teeth may be inclined in order 30 to effect an additional transverse displacement, which, however, is not indispensable. It is also possible to form the teeth in the manner of the well known herringbone teeth with advancing or following points.

35 In the drawings affixed to the specification and forming part thereof, several devices embodying my invention are illustrated by way of example. In the drawings—

40 Figs. 1 and 3 are elevations showing the toothed faces of the gripping pawls while

Fig. 2 is an elevation of the pawls in operative position.

45 Figs. 4 and 5 illustrate a modification of the pawls in inoperative and operative position, respectively,

Figs. 6 and 7 are sections of part of a cage or the like, on which my improved device is arranged.

50 Referring now to Figs. 1 to 3, the pawls *l* which are adapted to turn on pivots *k*, are provided on their faces with teeth *m* with slots *s* between them. The teeth are connected by cheeks *t*, on either side so that a box like chamber is formed, which the chips detached by the teeth enter, where-

upon they fall out of the pawls. If, as illustrated, the teeth are arranged at an angle, the teeth above the cheeks *t* can not be clogged either as here the chips either enter the slots *s* or are immediately thrown out. The teeth above the cheeks *t* might also be cut away up to the cheeks so that they are exposed on their entire effective width. Instead of arranging the teeth between two cheeks, as shown, in smaller devices, only a central rib may be provided, the teeth projecting on either side of said rib.

Obviously by this invention the problem is solved of preventing the clogging of the teeth so that their operation is reliable. Consequently, the motion of the cage or the like is retarded to a limited extent when the rope breaks. This retarding is effected by a regular change of form, as by detaching 75 chips. The chips are successively removed by the teeth and removed to the rear as in a planer.

The gripping pawls so constructed performing the work of lifting chips which is necessary for producing with sufficient reliability a predetermined retarding action, it is also necessary to safeguard the effectiveness of the improved gripping pawls in other respects.

80 To this end several improvements had to be made which are illustrated in Figs. 4-7.

Figs. 4 and 5 illustrate the gripping pawls in inoperative and operative position, respectively.

90 Figs. 6 and 7 are longitudinal sections of the upper portion of a cage showing the means for operating the gripping pawls, and in particular their kinematic relation to the vertical rod (king rod), arranged at the 95 centre of the cage to which the rope is attached.

The work of detaching chips necessary for a limited retardation differs according to 100 whether the guide rails are comparatively new or worn. With the usual fixed stops of the gripping pawls heretofore used, which are rigidly secured to the cage, the pawls would in the first case perhaps be forced far too much into the wood, and in the second case, too little.

110 The disturbance of the operation of the gripping device which is caused thereby is avoided according to my invention by automatically making the penetrating depth of the pawl teeth dependent of the extent to which the guide rails are worn. This

is effected by providing the pawls *l* with ball shaped extensions *a*, by which they engage the guide rails *b* directly, so that with new guide rails the pawls are farther apart than with worn rails. Consequently, the depth of penetration will be the same with new as well as with worn guide rails. With this arrangement a further development of my invention can be combined which considers the fact that the guide rails must be interrupted at the several levels of the shaft to render the cages easily accessible. Here, it might occur, that the pawls engage one another so that they would engage the guide rails at an obtuse angle, after the mouth of the gallery has been passed. In order to avoid this, rigid stops are provided in combination with the ball shaped extensions *a* so that the pawls are prevented from engaging by these stops engaging a guide shoe *d*. Obviously there is normally a clearance between the stops *c* and the guide shoe *d*, as the depth of penetration of the pawls *l* is determined by the ball shaped faces *a* sliding on the guide rails *b*.

The arrangement of the guide shoe *d* at the point indicated has also a particular object. Heretofore, the guide shoes *d* were as a rule arranged above the pawls where the guide rails are worn already by the operation of the gripping devices. As here, however, the guide shoes *d* are below the gripping pawls *l*, they will remain permanently effective as they still engage the portion of the guide rails *d* which is not worn. At the same time the shoes *d*, as explained, above, form a ready means for controlling the stops *c* of the gripping pawls *l*.

This arrangement also allows to place the pivots *k* of the gripping pawls *l* so far apart, that under the action of the pawls there is sufficient leverage to prevent under all conditions a disengagement of the gripping pawls. Heretofore, the pawls *l* were placed so near the guides *b*, that the pawls were inclined at a comparatively great angle (Figs. 1 and 2) whereby, the danger was created of the pawls becoming disengaged so that special locking devices had to be provided. The arrangement according to Figs. 4 to 5 permits to avoid this drawback in a different manner.

There is another cause of obstruction which must be removed. As is well known, the engaging movement of the gripping pawls is made dependent upon the vertical rod *e*, which is under the action of a strong spring *f*. As long as the spring *f* is compressed by the weight of the cage and the rope is not broken, the pawls are disengaged. When the rope *g* breaks, spring *f* will expand and cause the gripping pawls *l* to engage, which are operatively connected with the rod *e*. With the arrangements

heretofore employed there appeared the phenomenon that the four gripping pawls will not engage the guide rails uniformly, but, for example, only these pawls will engage the guide rails which are disposed on diagonally opposite sides of the cage, so that the device does not operate correctly.

The cause of this phenomenon is, that the cinematic system composed of the vertical rod, gripping pawls and connecting rods is a self contained mechanism, that is a mechanism in which a movement of one member causes a definite movement of all other members. Since now the cage is held by the guide shoes, in a definite position in relation to the guide rails, it may happen that it is arrested by the engagement of a single gripping pawl. This is the consequence of the fact that the self contained mechanism becomes over-self contained, whereby also the part which the several gripping pawls take in the retarding action and the supporting of the cage becomes statically indefinite. The self contained mechanism is not able to adapt itself to these several conditions of support.

In order to remove this phenomenon which may seriously disturb the operation of the gripping pawls, the self contained mechanism is divided into several mechanical systems, all the gripping pawls or at least those pairs of pawls which are disposed at each front face of a cage, being provided with a separate spring, while the vertical rod only has to release a locking device which maintains the gripping pawls in locked position. Consequently, the gripping pawls will engage on either side without their kinematic dependency exerting a disturbing influence.

The particular arrangement employed to this end is the following: On the pivots *k* of the gripping pawls *l* there are disposed levers *h* which are held together by means of a clamp *i*, said clamp being acted upon by a spring *n*. The rod *e* operates the bell crank levers *o*, (Fig. 6) which by means of connecting rods *p* operate bolts *q*, which pass through the front walls of the cage and get into a position in front of the pawls *l*. When the rope *g* breaks and spring *f* expands, the rod *e* is withdrawn and the bolts *q* are withdrawn also so that the springs *n* are able to cause the gripping pawls *l* to engage. The independence hereby provided in a similar manner as in trip gears for steam engines permits an exact engagement of the gripping pawls on either side. In order to prevent damage to the rods *p* or bolts *q*, respectively, when the cage is raised again and the spring *f* is compressed, which might occur, as the bolts *q* now abut against the gripping pawls which are in operative position, the bolts *q* are provided with an extension *r* which engages rods *p*, so that they cannot

be bent downwards but yield upwards. All these parts are returned to normal position by moving apart the gripping pawls, which have engaged the guide rails, by means of 5 a screw or the like, so that the bolts q are able to move outwards in the manner illustrated in Fig. 6.

A further difficulty consists therein that all the parts of the system of links move with 10 considerable resistance. In the operation of a mine shaft where there is not sufficient attention and examination paid to the working of such a device, it may easily happen, that the several parts are stuck by rusting, 15 so that they can be moved only with difficulty or not at all. In order to avoid this, not only the bearings of my improved device are suitably constructed and suitable lubrication is provided, but those parts which are 20 particularly exposed to damage, are protected by special means. For example, the guide of the rod e is formed as a chamber u closed on either side by short insertions v and is maintained filled with grease by means of 25 grease boxes w , so that it can not become rusty on the inside and is further provided with lubricant in sufficient quantities. In the same manner, the springs n are constructed in frustoconical shape, and also 30 filled with grease by aid of suitable grease cups.

I claim:—

1. In a gripping device for lifts in combination, a cage, a grip jaw connected with 35 said cage, a wooden rail adapted to be gripped by said jaw and a plurality of superposed cutting teeth on said jaw spaced apart so as to allow chips of wood to pass between them.

2. In a gripping device for lifts in combination, a cage, a grip jaw substantially U-shaped in cross-section connected with said cage, a wooden rail adapted to be gripped by said jaw and a plurality of superposed 45 cutting teeth on said jaw spaced apart so as to allow chips of wood to pass between them.

3. In a gripping device for lifts in combination, a cage, a grip jaw substantially U-shaped in cross-section connected with said cage, a wooden rail adapted to be gripped by said jaw and a plurality of superposed cutting teeth on the grid-shaped middle web of said jaw.

4. In a gripping device for lifts in combination, a cage, a grip jaw connected with said cage, a wooden rail adapted to be gripped by said jaw, a plurality of superposed cutting teeth on said jaw spaced apart

so as to allow chips of wood to pass between them and a smooth cheek formed on the lower portions of said jaw. 60

5. In a gripping device for lifts in combination, a cage, a grip jaw connected with said cage, a wooden rail adapted to be gripped by said jaw, a plurality of superposed cutting teeth on said jaw spaced apart so as to allow chips of wood to pass between them, a projection on said jaw and a stop on said jaw adapted to cooperate with said projection in limiting the gripping motion of said jaw. 65

6. In a gripping device for lifts in combination, a cage, a grip jaw connected with said cage, a wooden rail adapted to be gripped by said jaw, a plurality of superposed cutting teeth on said jaw spaced apart so as to allow chips of wood to pass between them and a guide shoe arranged underneath 70 said jaw. 80

7. In a gripping device for lifts in combination, a cage, a grip jaw connected with said cage, a wooden rail adapted to be gripped by said jaw, a plurality of superposed cutting teeth on said jaw spaced apart so as to allow chips of wood to pass between them, means for locking said jaw in inoperative 85 position and a king rod on said cage operatively connected with said locking means and adapted to release said jaw. 90

8. In a gripping device for lifts in combination, a cage, a grip jaw connected with said cage, a wooden rail adapted to be gripped by said jaw, a plurality of superposed cutting teeth on said jaw spaced apart so as to allow chips of wood to pass between them, a spring tending to move said jaw into operative position, means for locking said jaw in inoperative position and a king rod on said cage operatively connected with said locking means and adapted to release said jaw. 95

9. In a gripping device for lifts in combination, a cage, a grip jaw connected with said cage, a wooden rail adapted to be gripped by said jaw, a plurality of superposed cutting teeth on said jaw spaced apart so as to allow chips of wood to pass between them, means for locking said jaw in inoperative position and a king rod on said cage operatively connected with said locking means and adapted to release said jaw, the connection between said rod and said locking means being such that said means are free 105 to move upwards. 110

In testimony whereof I affix my signature.

PAUL SCHÖNFELD.
